(57) **CLAIM**

The ornamental design for a circular fabric article such as a towel, as shown and described.

DESCRIPTION

FIG. 1 is a top view of an embodiment of the circular fabric article such as a towel of the present invention;

FIG. 2 is a front/rear view of the circular fabric article such as a towel of FIG. 1;

FIG. 3 is a bottom view of the circular fabric article such as a towel of FIG. 1;

FIG. 4 is a side view of the circular fabric article such as a towel of FIG. 1;

FIG. 5 is a top view of an embodiment of the circular fabric article such as a towel of the present invention;

FIG. 6 is a front/rear view of the circular fabric article such as a towel of FIG. 5;

FIG. 7 is a bottom view of the circular fabric article such as a towel of FIG. 5;

FIG. 8 is a side view of the circular fabric article such as a towel of FIG. 5;

FIG. 9 is a top view of an embodiment of the circular fabric article such as a towel of the present invention;

FIG. 10 is a front/rear view of the circular fabric article such as a towel of FIG. 9;

FIG. 11 is a bottom view of the circular fabric article such as a towel of FIG. 9; and,

FIG. 12 is a side view of the circular fabric article such as a towel of FIG. 9.
